DESIGN FOR A REAR VIEW MIRROR OR THE LIKE

Glen A. Johnson, Connersville, Ind.

Application August 13, 1934, Serial No. 52,931

Term of patent 7 years

To all whom it may concern:

Be it known that GLEN A. JOHNSON, a citizen of the United States, residing at #2735 Grand Ave., Connersville, in the county of Fayette and State of Indiana, has invented new, original, and ornamental Design for a Rear View Mirror or the like, of which the following is a specification, reference being had therein to the accompanying drawing, forming a part thereof, in which—

Fig. 1 is a back view of the device showing my new design.

Fig. 2 is a side elevation of the device.
Fig. 3 is a perspective view of the device taken from the rear.

I claim:

The ornamental design for a rear view mirror or the like as shown.

In testimony whereof, I affix my signature.

GLEN A. JOHNSON.
